UNITED STATES PATENT OFFICE

JOSES T. LA MEASURE AND LAURENCE J. LA MEASURE, OF DETROIT, MICHIGAN

LINT COLLECTOR

Application filed July 29, 1927. Serial No. 209,210.

This invention relates to dust collectors and particularly to dust collecting attachments for rotary brushes.

- For cleaning garments and for various other purposes, light portable rotary brushes driven through suitable flexible shafts are now in use. The lint and dust by such brushes has not, however, been heretofore adequately taken care of, and has been allowed 10 to settle about the premises on which the brush is used or has required use of the brush adjacent to an outlet from such premises together with one or more fans for discharging such dust and lint through said opening. 15 It is an object of this invention to provide a light and inexpensive dust collecting attachment for a brush of the aforesaid character, keeping the air in the premises on which the brush is used clean and sanitary. 20 Another object is to provide a light fabric receptacle for dust removed from a garment or the like by a rotary brush, and to hold said receptacle expanded in use by a frame formed of wire or the like, having a suitable provision 25 for its attachment to and detachment from a casing partially enclosing said brush whereby the brush is adapted to deliver the dust and lint from the garment through said casing into said receiver. 30 Still another object is to provide a plate formed of sheet metal, or the like, within said fabric receiver to take the impact of the dust or lint discharging from the brush, said plate being preferably permanently carried 35 by said frame.

It is also an object of this invention to provide a thumb piece rigidly connected to the casing of the brush, and a handle member through which a drive shaft extends to the brush, said thumb piece facilitating a complete control of the brush by the operator's hand which grips said handle.

These and various other objects the invention attains by the construction hereinafter described and illustrated in the accompanying drawings herein.

Figure 1 is a perspective view of the unit formed by the encased brush, and the dust 50 and lint receiver.

Figure 2 is a longitudinal vertical sectional view of the same.

Figure 3 is a plan view of the same.

Figure 4 is an enlarged view in side elevation of the encased brush, showing primarily the detachable connection to the casing of the dust receiver. 55

Figure 5 is a cross sectional view of the same taken upon the line 5-5 of Figure 4.

Figure 6 is a perspective view of the frame 60 for spreading open the dust receiver.

In these views the reference character 1 designates a brush having radial bristles 1a, which brush is fastened upon shaft 2. Said shaft is journaled in a pair of bearings 3 rigidly carried by opposite walls of a substantially parallel circular casing 4, the lower portion of which is cut away, as indicated at 5, allowing the brush to project sufficiently for working engagement with a garment or other surface to be cleaned. From one of the bearings 3 there projects radially a tubular handle member 6 through which the shaft 2 extends. To the outer end of said handle member is connected in any suitable manner the flexible 65 tubular casing 7 of flexible drive shaft 8 through which the shaft 2 is driven. 70

The casing 4 is integrally formed with an outlet fitting 9 for dust and lint, projecting from the circular wall of said casing at substantially 90° to the opening 5, and upon said fitting is detachably mounted one end of a light elongated frame 10 formed of wire or the like, said frame being preferably of circular cross section and reduced somewhat in diameter towards its outer end as is best seen in Figures 2 and 6. As a preferred means for quickly securing said frame to the fitting 9 or disconnecting it therefrom the supported end of said frame comprises a split ring 11, 80 one end of which forms an eye 12 through which the other end of said ring is passed, as indicated at 13. At the juncture of the part 13 with the main body of said ring there is formed a shoulder 14, which, when passed through the loop 12 seats upon said loop to hold the ring snugly engaged in the annular groove 15 formed exteriorly in the fitting 9. 85

The dust receiver proper consists of an elongated fabric bag 22, proportioned to fit 100

snugly over the frame 10 and adapted to be held in place upon said frame by an elastic band 23 or the like, sewed or otherwise attached to the mouth of the dust receiver 22.

5 Interiorly secured to the top portion of the frame 10 is a scoop-shaped metal plate 16 extending lengthwise of the frame from the supported end thereof and serving to initially receive the impact of dust and lint which are 10 discharged by the brush 1 into the receiver 22.

To facilitate manipulation of a brush it is preferred to mount a thumb piece 17 upon the handle 6 adjacent to the casing 4. As is best seen in Figures 4 and 5, said thumb piece 15 is formed integral with an upper clamping member 18, which is secured by screws 19 or the like to a lower clamping member 20, the handle member 6 being rigidly engaged between said clamping members. The member 20 is carried by an arm 21 integrally projecting from a side wall of the casing 4.

In the use of the described device the operator grasps the handle 6 with his right hand, resting his thumb upon the member 17. 25 Power being applied to the shaft 8 from any suitable source the brush 1 is rapidly driven and the operator moves the device back and forth over the surface of the garment (or any other surface) to be cleaned, the dust and lint 30 removed from said surface by said brush being thrown through the fitting 9 into the receiver 22 and avoiding any contamination of the air or premises on which the device is used. The receiver 22 and its reinforcing 35 frame 10 are of such light construction as to add but little to the effort necessary to manipulate the unit back and forth over the surface being cleaned. When the receiver 22 requires to be emptied the fastening 12, 13 may 40 be readily released to permit removal of the frame 10, carrying said receiver. The thumb piece 17 assists the operator in applying and regulating the pressure of a brush against a garment or the like, and further facilitates 45 tilting the unit to establish the most suitable working angle thereof with respect to the surface engaged by the brush. The provision of the plate 16 prevents any dislodged particles of dust or dirt from being thrown 50 violently against the fabric wall, and consequently adhering thereto.

It is to be noted that only a slight clearance space is provided between the brush of the casing 4 so that the brush acts largely after 55 the manner of a fan tending to draw the dirt from the garment by suction, as well as by actual contact, and throwing such dirt, lint, etc., forcibly into the receiver. The construction is very light and inexpensive. While 60 the device is primarily designed for cleaning articles of wearing apparel it is to be understood that it is also applicable for removing dust and lint from any surface particularly a fabric surface.

65 While it will be apparent that the illus-

trated embodiments of our invention herein disclosed are well calculated to adequately fulfill the objects and advantages primarily stated, it is to be understood that the invention is susceptible to variation, modification and change within the spirit and scope of the subjoined claims.

What we claim is:

1. The combination with a rotary brush, of a casing formed with an opening through which a peripheral working portion of the brush projects, and further formed with a peripheral outlet for dust and lint, a dust receiver detachably connected to said outlet and projecting from the casing substantially transversely to the brush axis, a handle laterally extending from said casing, a drive shaft for said brush extending through said handle and a thumb piece mounted upon said handle adjacent to said casing and projecting from said handle substantially oppositely to the dust receiver, whereby the excess of weight carried by the casing at its dust receiver side may be counteracted by pressure applied to said finger piece. 70

2. The combination with a rotary brush, of a substantially circular casing within which said brush is journaled, said casing having a peripheral opening through which the brush projects, and further having an outlet opening through its periphery closely adjacent to said brush and substantially transverse to the first named opening, a fitting formed around said outlet, a fabric dust receptacle closed at one end, and means detachably mounting the other end of said receptacle directly upon said outlet fitting. 90

3. The combination with a rotary brush, of a cylindrical casing formed with a peripheral opening through which a working portion of said brush projects, a tubular handle member extending from said casing substantially in the direction of the extended axis of the brush, drive means for the brush passing through said handle, and a dust receptacle peripherally communicating with the casing and projecting therefrom substantially transversely to said handle. 105

In witness whereof we hereunto set our hands.

JOSES T. LA MEASURE.

LAURENCE J. LA MEASURE.
